UNITED STATES PATENT OFFICE

RAYMOND T. ANDERSON, OF CLEVELAND, OHIO, ASSIGNOR TO THE V. D. ANDERSON COMPANY, OF CLEVELAND, OHIO, A CORPORATION OF OHIO

PRESS

Application filed November 16, 1926. Serial No. 148,755.

This invention pertains to improvements in presses and more particularly that type employed for expressing of fluids from various materials. The press is of the same general type as that shown in Letters Patent to Anderson No. 731,734 dated June 23, 1903, and the main object of the invention is to provide various improvements in the structural features of such a press whereby better results may be obtained, a more efficient press produced and, furthermore, one which may be readily assembled and disassembled.

The structure is illustrated in the annexed drawings wherein,

Figure 1 is a vertical longitudinal view of the press;

Figure 2 a transverse vertical section taken on the line II—II of Figure 1 and on an enlarged scale;

Figure 3 a similar section taken on the line III—III of Figure 1;

Figure 4 a top plan view of a portion of the structure at the intake or hopper end of the press; and

Figure 5 a detail sectional view showing a slight modification of the means employed to effect a coupling between the worm carrying shaft and the driving shaft.

The structure is such that in action the shaft which carries the pressing worms is placed under tension whereby wobbling of the shaft is prevented to a greater or less degree over those presses wherein the shaft has its thrust bearing at the intake end of the machine and the pressure is exerted by the screws toward that end and against the bearing at that end. Again, the structure provides means whereby the shaft and the worms may be readily withdrawn in case of necessity and a new shaft with new worms substituted without any undue prolongation of the time of shutting down of the machine. Furthermore, the shell of the press is so formed and mounted that it may be readily opened and each section moved laterally away from the worms and the worm carrying shaft, the arrangement, moreover, facilitating better drainage of the expressed liquid or oil as it passes from the shell to a

collecting trough located beneath the shell.

In the drawings, referring first to Figures 1 to 4, both inclusive, 1 denotes the main frame of the press which is preferably made as an integral casting in order to afford proper support for the various elements associated therewith.

The shell of the press is composed of a series of bars 2 arranged in circular series, the bars in the present instance being carried by, and locked in position upon, heavy transversely disposed castings or rib-like members 3 and 3^a. The castings on each side of the shell are alike in form hence a description of one will suffice for the other. Each casting is provided at its upper and lower ends with a flat bearing face denoted, respectively, by 4 and 5. Bars 2, as in the former patent to Anderson, are held in place upon the semi-circular seat formed upon the member 3 (or 3^a) by shoe bars 6 and 7 and intermediate key bars 8, the latter being drawn to place after the other bars are positioned thus crowding the bars into their proper relation with the inner edges slightly spaced apart.

Knife bars 9 are also positioned between each pair of shoe bars 6—6 and 7—7. These knife bars, as will be best seen upon reference to Figure 1, are so constructed that the knives extend inwardly between the flights of the screws hereinafter described.

The frame members 3 and 3^a at the extreme ends of the shell rest upon tracks or ways formed by bars 10 and 10^a having flat upper faces, as best shown in Figure 3. These bars are secured directly to fixed portions of the frame of the machine and form a support for the shell and its component parts. To hold the elements 3 and 3^a in their proper working relation to each other and consequently to hold the semi-circular shell sections together to produce the completed circular shell, I provide transversely disposed studs or bolts 11 and 12, which studs or bolts are threaded at one end into upper and lower clamping bars 13 and 14, respectively, the studs at their opposite ends passing through openings formed in a second pair of clamping bars 15 and 16. The studs

or bolts, as will be seen upon reference to Figures 1 and 3, are arranged in horizontal position and pass between the adjacent ends of the series of members 3—3^a. The bars 13 and 15 take against the upper flat faces 4 and 4^a while the lower pair of bars 14 and 16 take against the flat faces 5 and 5^a. By turning up the nuts 17 upon the bolts, the members 3 and 3^a throughout the series will be drawn firmly together thus insuring a proper conformation to the shell composed of the bars 2 and their associated shoe and key bars. The bars 10 and 10^a prevent any downward motion of the shell and the longitudinally extending bars 13, 14, 15 and 16 prevent any transverse movement of the component elements of the shell; thus the shell may be said to be held against movement in three directions.

As will be readily appreciated from the foregoing, by loosening the nuts 17 one or both of the sections of the shell may be moved laterally and maintained in such lateral position, if desired, in order to afford access to the interior of the shell for the replacement of any of the bars or for access to the worms or for any purpose. The arrangement, moreover, is advantageous in that the foots or fine materials extruding through the barrel slots with the expressed liquids are washed down into the base of the expeller, or the trough formed therein, while in the prior Anderson constructions the foots extruding from the upper half are apt to collect and not go down into the base, as the space between the barrel bars and the clamping bar studs is quite restricted.

The main frame is provided as is usual with a feed hopper 18. Extending through the shell is a shaft 19, the shaft extending laterally to the right of the hopper and likewise extending outwardly beyond the discharge end of the press where it coacts with radial and thrust bearings shortly to be described. At the right hand end of the machine the shaft 19 is keyed or splined to a sleeve 20 supported in suitable bearings 21 and 22, said sleeve having keyed thereon a driving gear 23 to which motion may be imparted in any suitable manner. A sprocket wheel 24 is secured to the innermost end of the sleeve or member 20, said sprocket being utilized for the purpose of driving the tempering apparatus, not shown, commonly employed in conjunction with a press of this type where certain materials are undergoing treatment.

Keyed to the shaft 19, adjacent the hopper end thereof, is a sleeve 25 carrying one or more feed worms or screws 26 which tend to draw the material from the hopper and feed the same into the shell of the press. The outermost end of said sleeve 25 is provided with an enlargement 27 which takes against a shouldered portion 28 formed upon the

shaft 19. This enlarged portion closes the opening in the hopper through which the shaft extends and makes for rigidity of said member 25 affording proper amount of metal for keying the member 25 to the shaft.

Located inwardly of the feed worm is an inclined collar 29 which encircles the shaft and located beyond said collar is a series of separated worms or screws 30 spaced apart by suitable washers 31. These pressing worms are keyed to the shaft so as to rotate therewith.

Beyond the last worm the shaft has keyed to it a sleeve 32, which sleeve extends through a discharge opening the size of which may be regulated in any desired manner. In the instant case a series of jaws 33 carried by slides 34 is illustrated, which slides may be moved radially inwardly and outwardly and held in their adjusted position by an actuator 35 which is provided on its periphery with a thread with which cooperates a worm 36. This arrangement, however, is not herein specifically claimed as it forms the subject matter of my copending application filed on or about May 28th, 1925, Serial Number 33,461.

By adjustment of the jaws 33 greater or less pressure may be had within the shell.

Extending outwardly from the housing 37 of the choke mechanism is a frame or casting 38 which is open at its lower side and likewise preferably provided with lateral openings. A third sleeve 39 is keyed to that section of the shaft 19 which lies within the member 38, the outermost end of the sleeve passing into a hollow box or casting 40 surrounding the shaft and held in position within the outer end of the member 38 by a plate 41, said plate in turn being secured to a flange 42 formed upon the member 38 by bolts 43 which pass through the plate 41 and into the flange 42, said bolts likewise passing through a flange 44 formed as an integral portion of a hollow head or casting 45. The member 40 provides a drainage chamber for any fluid which may be forced outwardly along the shaft between the sleeves thereon, the end of the sleeve 39, which lies within the chamber, being notched to permit the outflow of such liquid.

The member 45 forms the support for the radial and thrust bearings employed in connection with the shaft 19. Surrounding that portion of the shaft 19 which lies within the housing 45 is an elongated collar 46, the collar abutting the end of the adjacent sleeve 39 and being threaded and having mounted thereon a nut or abutment 47 locked to the collar 46 in any suitable manner as by a pin 48.

Rollers 49 interposed between races 50 and 51 positioned as shown in Figure 1 with reference to the collar, the nut 47 and the housing 45 form the lateral bearing for the outer end of the shaft. Races 52 and 53 with asso-

ciated rollers 54 provide the thrust bearing for the press, the races being held in proper position by taking against a shoulder 55 formed upon the housing 45 and against 5 a flange 56 formed upon the collar 46. A nut 57 is mounted upon the outer threaded end of the shaft 19 and takes against the flange 56, the nut being locked in position by any suitable means. A cover plate 58 and a plate 10 59 are secured to the outer end of the housing 45. The plate 59, along with the plate 41, acts to form a reservoir for holding lubricant in and around the bearings.

As is known to those skilled in the art, the 15 cake which is forced out of the press through the discharge opening will, in certain instances, be extremely hard. It has been found in practice that the cake will pass along the outer end of the sleeve 32, follow the sleeve 20 39 and be forced or jammed up into the casting 38 and against the hollow liquid receiving member 40. To prevent such action taking place, I provide a simple means for disrupting the cake. This may consist of two 25 straps or castings 60 and 61, Figures 1 and 2, the ends of which are threaded to receive machine screws 62 to clamp them together and cause them to embrace the sleeve 39. By 30 loosening one, or both, of the screws the members 60 and 61 may be moved toward or from the discharge opening or choke of the press according to the condition of the cake.

The frame of the press below the shell or barrel thereof is provided with a trough 63 35 having a gutter or channel 64 formed in the lower portion thereof. A screw conveyor 65 works in this channel, said conveyor being mounted upon a shaft 66 which receives its motion from any suitable source, not shown. 40 This conveyor acts to thoroughly intermix the foots and liquid passing from the press and prevents clogging of the pumps to which the material is passed from the channel 64.

The press as above constructed operates in 45 the main the same as it does in the Anderson patent, above referred to. The material is drawn in by the feed worm 26, is moved through the shell and disrupted and compressed by the screws 30, the oil being forced 50 outwardly between the narrow openings between the bars of the shell. The cake is extruded past the choke and is finally discharged through the openings in the frame or casting 38. Due to the action of 55 the screws upon the material within the shell a pull or tension is placed upon the shaft 19 toward the right or the intake end of the machine. This is taken care of by the thrust bearing and inasmuch as the 60 shaft is held under tension, tendency of the shaft to wobble and to cause the screws to contact the bars and to peen their edges down is obviated. This freedom of contact between the screws and the shell does away 65 with any movement of the shell as a whole.

In case it becomes necessary to withdraw the shaft 19 and the worms, the cover 58 is first removed, then nut 57 followed by the removal of the bolts 43. The case 45, with its assembled parts, can then be removed from 70 the casting 38 and shaft 19. Castings 60 and 61 are then released and the choke jaws 32 are retracted. The shell is then opened up by removing the nuts 17 followed by the removal of the bars 13, 14, 15 and 16. The shaft 19, 75 with the feed screw 26 and the worms 30, can then be withdrawn. A new shaft with new sleeves, worms and screw may then be readily inserted and this without in any wise necessitating a demounting or a re-arrangement of the driving means at the head end of the machine.

Any form of separable connection may be employed between the inner end of the shaft and the driving mechanism and in Figure 5 85 I have shown a short hollow shaft 67 to which the driving gear 23 is splined. Said shaft 67 is provided with a plurality of integral splines 68 on its inner face or bore which interfit with similar splines 69 formed upon 90 the outer face of the adjacent end of the shaft 19.

By so mounting the shaft that it is placed under tension when the press is in action and by employing a frame produced from a single casting or pressed up from steel, great 95 rigidity inheres in the structure and there is less opportunity for relative movement of displacement of the parts than with structures wherein the shaft is not under tension 100 or where the frame is composed of several elements bolted or otherwise secured together even though the shaft be under tension.

As will be noted upon reference to Figure 1, the feed screw 26 has a steep or quick pitch 105 whereas the worms 30 have a slow pitch. In actual practice feed screw or worm 26 has approximately a pitch of twelve inches to one turn whereas the worms have a pitch approximating four inches per turn. Thus the material which is to be treated and which is fed into the hopper 18 in a relatively loose or uncompacted condition will be fed forward rapidly by the flight or screw 26 to the feed worms 30 where, of course, the material becomes 110 denser or more fully compacted and its progress through the shell becomes slower.

Having thus described my invention, what I claim is:

1. In a press, the combination of a bed 120 frame; a pair of spaced, horizontally disposed ways supported thereby; a shell composed of two separable sections mounted for lateral movement on said ways toward and from each other; and means for rigidly securing said sections together.

2. In a press, the combination of a bed 125 frame; a pair of spaced, horizontally disposed ways carried thereby; a shell composed of two separable sections mounted for lateral move- 130

ment on said ways; and transversely extending bolts securing said sections together in working relation.

3. In a press, the combination of a bed frame; a pair of horizontally disposed ways carried by the frame, one adjacent the intake end and the other adjacent the discharge end of the press; a shell composed of two sections, the line of division between said sections lying in a plane extending longitudinally and vertically of the press, said sections being supported at their ends on said ways; and means for securing said sections together.

4. A press as set forth in claim 3 wherein each section of the shell comprises a series of vertically disposed spaced ribs, each rib having a recess formed in its inner face, and a series of bars seated upon and secured against the face of said recess; combined with longitudinally extending bars bearing against the outer faces of the ribs, at their upper and lower ends; and transversely extending bolts connecting the bars in upper and lower pairs.

5. In a press, the combination of a base frame; a shaft carried in bearings supported by the frame; a series of worms mounted on the shaft; a longitudinally divided shell carried by the frame, the sections whereof are mounted for movement in a horizontal line toward and from each other and to and from the axis of the shaft; and means for rigidly securing said sections together in their assembled or closed position thereby producing a shell which surrounds the shaft and worms.

35 6. In a press, the combination of a bed frame; a pair of spaced horizontally disposed ways supported thereby; a multipart separable shell resting upon and supported by said ways; and means for rigidly securing the shell parts together in their assembled position whereby a non-yielding shell is produced.

In testimony whereof I have signed my name to this specification.

45 RAYMOND T. ANDERSON.
